DESIGN FOR A DISH OR SIMILAR ARTICLE

Louis E. Hellmann, Great Neck, N. Y., assignor to Continental Ceramics Corporation, New York, N. Y., a corporation of New York

Application September 22, 1933, Serial No. 49,314

Term of patent 7 years

To all whom it may concern:

Be it known that I, LOUIS E. HELLMANN, a citizen of the United States, residing at Great Neck, L. I., County of Nassau, and State of New York, have invented a new, original, and ornamental Design or a Dish or Similar Article, of which the following is a specification, reference being had to the accompanying drawing, forming a part thereof.

Fig. 1 is a side elevation of a dish showing my new design; Fig. 2 is a top plan view of the dish shown in Fig. 1, and Fig. 3 is a perspective view of the same dish.

I claim:

The ornamental design for a dish or similar article as shown.

LOUIS E. HELLMANN.
